PROCESS OF REFINING MARINE OILS

Loran O. Buxton, Newark, N. J., assignor to National Oil Products Company, Harrison, N. J., a corporation of New Jersey

No Drawing. Application July 13, 1942,
Serial No. 450,762

9 Claims. (Cl. 260—426)

This invention relates to a new and improved process for refining fatty materials, particularly vitamin-containing oils of marine origin.

The treatment of fatty materials with a small amount of caustic alkali, commonly termed "alkali refining," in order to refine the same has been practiced for many years. This process has certain major disadvantages. The treatment invariably fails to remove all of the undesirable taste, color and odor associated with the crude fatty materials and in certain instances, particularly in the case of fatty materials of fish origin, the caustic alkali has a harmful effect on certain components present in the fatty material resulting in the production of characteristic undesirable tastes and odors in the alkali refined material. Certain hydroxylated compounds, highly unsaturated compounds and amine compounds in fatty materials of fish origin are affected detrimentally by the alkali treatment and are converted into undesirable constituents which are not effectively removed with the soaps that are formed.

It is the object of this invention to provide an improved process for the refining of fatty materials.

It is a further object of this invention to provide an improved process for refining vitamin-containing oils of marine origin.

Other objects of the invention will in part be obvious and will in part appear hereinafter.

I have discovered that fatty materials devoid of taste and odor may be obtained by first saponifying the fatty material to be refined with an amount of alkali sufficient to saponify all of the free fatty acids present in the fatty material and at least two to three per cent of the neutral glycerides, separating the soaps from the unsaponified glycerides, and contacting the unsaponified fatty material with a highly polar solvent immiscible with fatty materials. The polar solvent will remove taste and odor constituents not removed along with the soaps, and also a large proportion of any coloring matter contained in the fatty material and not removed with the soaps, thus giving a highly desirable bland, odorless, light-colored highly refined material. Also, in the case of vegetable oils, any so-called "break" constituents contained therein will be substantially all removed by the solvent treatment. In most instances it is preferred to saponify between about 5% and about 40% of the fatty material, preferably from 10% to 30%, depending upon the fatty material to be treated, as will appear hereinafter. Thus

in most instances a larger proportion of the fatty material is saponified than in the usual alkali refining processes. By so doing, the undesirable constituents of the fatty material will be removed to a greater extent than in such processes and those undesirable constituents which are not removed, if they are not already in such form, will be converted to a form in which they will readily be removed from the unsaponified fatty material by the treatment with the highly polar solvent. The process of the invention is particularly applicable for the refining of fat-soluble vitamin-containing marine oils, particularly vitamin-containing oils of fish origin. Such oils may be refined very effectively without hydrolyzing any appreciable portion of the natural vitamin esters contained therein provided the saponification step is carried out as hereinafter described. Any vitamin alcohols originally present in the oil and the small amount of such alcohols that may be produced by the saponification step, will be removed from the vitamin-containing oil by the extraction with the polar solvent along with the taste and odor constituents and a large portion of the coloring matter not removed in the saponification step, thus producing a highly refined, bland, odorless, light-colored vitamin-containing oil in which the vitamins are all present in their naturally-occurring ester form. The vitamin alcohols may be readily recovered from the highly polar solvent by any suitable means and employed for purposes for which they are suitable.

Any fatty material which it is desired to improve the taste, color and odor thereof may be refined by the process of this invention. Thus vegetable oils such as cottonseed oil, soybean oil, palm oil, corn oil, corn germ oil, wheat germ oil, sesame seed oil, teaseed oil, linseed oil, peanut oil, etc., may be refined by this process. Animal fats, oils such as lard oil, whale oil, seal oil, etc., may also be treated. However, the process of the invention is particularly applicable for the refining of vitamin-containing oils of marine origin. Thus, one may treat oils such as cod liver oil, ling cod liver oil, shark liver oil, sole liver oil, spear fish liver oil, tuna liver oil, pollack liver oil, sardine oil, mackerel liver oil, menhaden oil, herring oil, etc. Such oils when refined by the process of this invention contain substantially all of the natural vitamin esters originally present therein.

It is preferred to employ concentrated aqueous potassium hydroxide for the alkali refining step; however, any other suitable alkaline agents may

be used, such as sodium hydroxide, sodium carbonate, potassium carbonate, etc. The saponification may be carried out in any suitable manner. Thus, the saponification may be carried out in the presence or absence of an inert solvent, preferably a hydrocarbon or halogenated hydrocarbon solvent. Suitable solvents for this purpose include, *inter alia*, ethylene dichloride, methylene dichloride, trichlorethylene, heptane, hexane, cyclohexane, methyl cyclohexane, etc., or a mixture of such solvents. Also if desired, a saponification catalyst, e. g. isopropanol, may be employed in the saponification step. When the saponification is carried out in the presence of a solvent, the solvent should comprise from 15% to 99% and preferably 25% to 75% based on the weight of the oil. The saponification may be carried out at room temperature or temperatures above room temperature although when vitamin-containing oils are being saponified it is preferred that the saponification be carried out at room temperature or slightly above room temperature in order to obtain a rather slow rate of saponification for reasons as will appear hereinafter.

In the saponification of a non-vitamin-containing oil, the rate of saponification is relatively immaterial; however, in the case of vitamin-containing marine oils, it is preferred that a relatively slow rate of saponification be employed since it has been found that the natural vitamin esters are not hydrolyzed to any appreciable extent when such conditions of saponification are employed. Thus in saponifying a vitamin-containing marine oil it is preferred to carry out the saponification at room temperature either with or without the presence of an inert solvent of the type described above. In some cases when saponifying at room temperature it is desirable to use a catalyst such as isopropanol to bring about the reaction between the fatty material and the alkali. This is particularly true when saponifying in the presence of a solvent.

The degree of saponification will depend to some extent upon the purpose for which the refined fatty material is to be employed. However, in all instances sufficient alkali should be employed to saponify all of the fatty acids and at least 2 or 3% of the neutral fatty material triglycerides, and in most cases it is desired that sufficient alkali be used to saponify about 10% of the triglycerides. In some instances enough alkali may be employed to saponify up to about 40% of the fatty material. In the case of non-vitamin containing oils which are usually refined for the purpose of obtaining suitable oils for use as salad oils and similar edible purposes, the lower limits of saponification will be employed, since it is desired, of course, not to destroy any more of the oil than necessary. However, in the case of the refining of the vitamin-containing oils it may be desirable to saponify up to as high as 40% thereof, since such a degree of saponification may be carried out without hydrolyzing any substantial amount of the natural vitamin esters and thus in addition to refining the oil a certain amount of concentration of the vitamins will be effected.

After the saponification of the fatty material has been effected, the saponified oil may be separated from the soaps in any suitable manner, e. g. solvent extraction, centrifugation, etc. Preferably the saponified mass is extracted with a hydrocarbon or halogenated hydrocarbon solvent of the aforementioned type. The solvent solution of the unsaponified oil is removed from the soap

mass and the solvent removed therefrom to recover the partially refined oil.

The partially refined oil is then contacted with a highly polar solvent which is relatively immiscible therewith. The term "polar solvent" is employed herein to connote an organic solvent containing a polar functional grouping, i. e. a functional grouping which tends to produce an unbalanced electronic structure and thereby activate the molecule and impart a characteristic dipole moment thereto; examples of such polar functional groupings are the hydroxyl group, the carbonyl group, and the ester grouping. Such polar solvents which may be used in carrying out the process of the invention include, *inter alia*, methyl alcohol, ethyl alcohol, isopropyl alcohol, n-propyl alcohol, acetone, diacetone alcohol, ethyl acetate, methyl acetate, and methyl ethyl ketone, the last seven named solvents all containing at least 9% of water. Methyl alcohol and ethyl alcohol may contain any suitable quantity of water or no water at all. Suitable mixtures of the above solvents may also be used. The solvents which I prefer to employ in the practice of the present invention are methyl and ethyl alcohol and 85% to 91% aqueous isopropanol. A solvent sold under the trade-mark "Solox" by U. S. Industrial Chemicals, Inc. was found to be quite efficacious in practicing this invention. The solvent "Solox" is prepared by admixing 5 volumes of wood alcohol to every 100 volumes of ethanol and admixing to every 100 volumes of said mixture 1 volume of aviation gasoline and 5 volumes of ethyl acetate. The undesirable taste and odor constituents which it is desired to extract from the fatty materials are soluble in these solvents at room temperature, whereas the fatty materials themselves are immiscible therewith or relatively so even at higher temperatures.

In carrying out the polar solvent extraction step the partially refined oil is first mixed with the particular solvent to be employed. The relative proportion of solvent to oil may vary widely; the ratio of solvent to oil should be greater than one and preferably 2 to 50 parts of solvent to 1 part of oil. If desired, the mass may be warmed to a temperature slightly or substantially above room temperature, preferably with agitation. The solvent solution and the fatty material may then be separated from each other at the elevated temperature, or the mixture may first be allowed to cool to room temperature or cooled to a temperature below room temperature before completing this step of the process. Furthermore, if desired, a continuous process of extraction may be employed. Preferably the extraction is carried out in an inert gas atmosphere when vitamin oils are being treated.

The oil which has been contacted with the polar solvent is then freed of any solvent entrapped therein, and the solvent is also removed from the solvent extract by any suitable means such as, for example, vacuum distillation. The refined oil which is obtained will be bland, odorless and light-colored and in the case of a vitamin-containing oil will contain substantially all of the vitamin esters present in the original oil. Vegetable oils refined by this process will also be substantially free of "break" constituents. The material which is extracted from the oil with the highly polar solvent will contain taste and odor constituents not removed by the saponification step and a large proportion of the coloring constituents of the unsaponified oil. This fraction 75 will also contain any vitamin alcohols originally

present in the fatty material and any vitamin alcohols produced by hydrolysis of the vitamin esters during the partial saponification step.

For a fuller understanding of the nature and objects of the invention, reference should be had to the following examples which are given merely to further illustrate the invention and are not to be construed in a limiting sense, all parts given being by weight, and all vitamin potencies being expressed in U. S. P. units.

Example I

100 parts of crude tuna liver oil possessing a strong fishy odor and taste and dark red color were mixed with 3 parts of isopropanol and sufficient 45% aqueous KOH (4.0 gms.) to saponify about 10% of the oil. The mixture was stirred for 30 minutes and then left at room temperature for 12 hours. The mass was mixed with 400 parts of ethylene dichloride and then filtered. The solvent was removed under reduced pressure from the resulting oil which possessed a slight fish taste and odor, was medium golden yellow in color, and had a characteristic concentrate taste and odor.

75 parts of the alkali treated oil were extracted three times at -18° C. with 300 ml. portions of 98% methanol. The methanol soluble fractions as well as the insoluble fraction were freed of solvent. The methanol soluble fraction possessed a strong fishy and concentrate taste and odor as well as a dark brownish red color. The methanol insoluble fraction which contained the major portion of the vitamins A and D present in the crude oil was a light golden yellow and was completely without odor and taste. The vitamins were all present in their natural ester form.

Example II

300 parts of crude halibut liver oil containing 112,000 I. U. of vitamin A/gm. and having a strong fishy taste and odor were mixed with 9 parts of isopropanol and 150 parts of ethylene dichloride and then sufficient 45% aqueous KOH to saponify about 28% of the oil was added. The saponification and the extraction of the unsaponified oil were carried out as in Example I. The resultant oil which had a slight fishy, characteristic concentrate taste and odor and which was rather dark in color was extracted with methanol as in Example I. The methanol insoluble fraction which had a potency of 139,200 I. U. of vitamin A/gm. and contained about 88% of the vitamin A originally present in the oil, the vitamins being present in their naturally-occurring ester form, was much lighter in color than the partially refined oil and was without taste and odor. The methanol soluble fraction contained most of the taste, odor and color constituents originally present in the crude oil as well as the vitamin alcohols originally present therein, and the small amount of vitamin alcohols produced in the alkali refining step. This fraction which contained about 12% of the vitamin A originally present in the crude oil had a potency of 515,500 I. U. of vitamin A/gm. and was highly suitable for use in the fortification of low potency vitamin-containing oils employed for poultry and animal purposes.

Example III

300 parts of shark liver oil containing 157,000 I. U. of vitamin A/gm. and which had a decided fishy taste and odor were refined as in Example II, except that 37.5% of the oil was saponified. A light colored, odorless, bland oil which had a

potency of 222,400 I. U. of vitamin A/gm. and which contained about 87% of the vitamins originally present in the oil was obtained. The vitamins were present in the oil in their naturally-occurring ester form. The remainder of the vitamins originally present in the crude oil were contained in the methanol soluble fraction which had a potency of 514,000 I. U. of vitamin A/gm.

Example IV

10 A crude shark liver oil was treated as in Example II except that 40% of the oil was saponified. The methanol insoluble fraction which was a light-colored, bland, odorless oil contained about 15 87% of the vitamins present in the original oil with the vitamins being present in their naturally-occurring ester form. The methanol soluble fraction contained substantially all of the vitamin alcohols which were present in the unsaponified oil and the taste and odor constituents thereof along with the major portion of the coloring matter thereof.

Example V

25 100 parts of crude tuna liver oil containing 73,000 units of vitamin A/gm. and 20,000 units of vitamin D/gm. were mixed with 3 parts of 99% isopropanol and while stirring in the presence of N₂ gas sufficient 45.5% aqueous KOH (4.0 parts) to saponify about 10% of the oil was added. After 30 30 minutes the stirring was ceased and the mass left at room temperature for 3 hours. After adjusting the moisture content of the soap to about 25%, the mass were mixed with 400 parts of ethylene dichloride and the mixture gravity 35 filtered. The clear filtrate was freed of solvent. The resulting oil was greatly improved in color, taste and odor. The alkali treated oil, however, was still slightly fishy and had acquired a slight 40 characteristic concentrate taste and odor. The vitamin recovery was substantially 100%.

45 50 parts of the above alkali treated oil was mixed with 100 parts of 91% isopropanol and the mixture thoroughly agitated. The mixture was then cooled gradually to -27° C. and filtered. The insoluble oil was extracted twice more essentially as before. The extracts were combined and freed of solvent. The resulting oil possessed a strong fishy and slight concentrate taste and odor. The alcohol insoluble oil after being freed 50 of traces of solvent was completely bland and greatly improved in color. The vitamin A and D ester content was essentially the same as that of the crude oil.

55 *Example VI*

60 100 parts of crude soy bean oil were saponified according to the process of Example I, 10% of the oil being saponified. The unsaponified oil was 65 recovered by extracting the mass with ethylene dichloride and recovering the oil therefrom as before. The alkali treated oil was then extracted with methanol as in Example I. The refined oil which was obtained was highly satisfactory in all respects being light golden yellow in color and free of undesirable tastes, odors and "break" constituents.

65 By the process of the invention it is thus possible to produce highly refined fatty materials 70 which are bland, odorless and light-colored; and in the case of vitamin-containing marine oils substantially all of the original vitamin esters are present therein. Oils and fats refined by the process of this invention are applicable for a wide variety of uses.

The phrase "continuous extraction" is employed in the specification and claims to connote both the usual type of continuous extraction and also what is usually referred to as counter-current extraction.

Selective partial saponification of vitamin-containing oils to produce oils in which the vitamin content of the original oil is concentrated there-in in naturally-occurring ester form and the fractionation of such concentrated materials to separate therefrom any vitamin alcohols originally present therein or produced by the saponification process to provide both concentrates of natural vitamin esters and concentrates of vitamin alcohols are specifically disclosed and claimed in my copending applications Serial No. 450,757 and Serial No. 450,759, filed concurrently herewith.

Since certain changes may be made in carrying out the above process without departing from the scope of the invention, it is intended that all matter contained in the above description shall be interpreted as illustrative and not in a limiting sense.

Having described my invention what I claim as new and desire to secure by Letters Patent is:

1. A process of refining a fatty material comprising the steps of saponifying all of the free fatty acids and a minor portion of the glycerides present in a fat-soluble vitamin-containing marine oil, removing the unsaponified oil from the resulting soap and extracting the soap-free oil with an organic polar solvent immiscible with fatty materials to remove odor, taste and color bodies therefrom.

2. A process of refining a fatty material comprising the steps of saponifying all of the free fatty acids and 5% to 40% of the glycerides present in a fat-soluble vitamin-containing marine oil, separating the unsaponified oil from the resulting soap and extracting the soap-free oil with an organic polar solvent immiscible with fatty materials to remove odor, taste and color bodies therefrom.

3. A process of refining a fatty material comprising the steps of saponifying all of the free fatty acids and 5% to 40% of the glycerides present in a fat-soluble vitamin-containing marine oil, separating the unsaponified oil from the resulting soap and extracting the soap-free oil with methanol to remove odor, taste and color bodies therefrom.

4. A process of refining a fatty material comprising the steps of saponifying all of the free fatty acids and 5% to 40% of the glycerides present in a fat-soluble vitamin-containing marine oil, separating the unsaponified oil from the resulting soap and extracting the soap-free oil with ethanol to remove odor, taste and color bodies therefrom.

5. A process of refining a fatty material comprising the steps of saponifying all of the free fatty acids and 5% to 40% of the glycerides present in a fat-soluble vitamin-containing marine oil, separating the unsaponified oil from the resulting soap and extracting the soap-free oil with isopropanol containing at least 9% water to remove odor, taste and color bodies therefrom.

6. A process of refining a fatty material comprising the steps of saponifying all of the free fatty acids and 10% to 30% of the glycerides present in a fish liver oil, separating the unsaponified oil from the resulting soap and extracting the soap-free oil at a relatively low temperature with an organic polar solvent immiscible therewith to remove odor, taste and color bodies therefrom.

7. A process of refining a fatty material comprising the steps of saponifying all of the free fatty acids and 10% to 30% of the glycerides present in a fish liver oil, separating the unsaponified oil from the resulting soap and extracting the soap-free oil at a relatively low temperature with methanol to remove odor, taste and color bodies therefrom.

8. A process of refining a fatty material comprising the steps of saponifying all of the free fatty acids and 10% to 30% of the glycerides present in a fish liver oil, separating the unsaponified oil from the resulting soap and extracting the soap-free oil at a relatively low temperature with ethanol to remove odor, taste and color bodies therefrom.

9. A process of refining a fatty material comprising the steps of saponifying all of the free fatty acids and 10% to 30% of the glycerides present in a fish liver oil, separating the unsaponified oil from the resulting soap and extracting the soap-free oil at a relatively low temperature with isopropanol containing at least 9% water to remove odor, taste and color bodies therefrom.

50 LORAN O. BUXTON.
